 zerland

Application November 4, 1932, Serial No. 641,148
 In Germany November 25, 1931

10 Claims. (Cl. 175—363)

This invention relates to improvements in rectifier control systems and more particularly to means for controlling the moment at which the anodes of an electron discharge device of the 5 gaseous or of the vapor type start carrying current during each cycle of the supply line.

It is well known that, in an electron discharge device, each anode may carry current only when such anode is at a positive potential with respect

- 10 to the cathode potential. Such flow of current may be prevented by maintaining a suitable control electrode at a potential below a so-called critical voltage which is generally approximately the cathode potential. Such flow of current may, 15 however, occur when the potential of the control electrode is not below such critical voltage and is variable dependent upon the conditions of pressure, of temperature within the device and upon the instantaneous voltage of the associated anode, and such action is frequently disturbed by the occurrence of so-called back fires during which the control electrode acts as a cathode to receive current from the cathode of the device which then operates as an anode. In addition, 20 the current flowing through a control electrode must be limited by insertion of resistance in the circuit thereof with the result that the source of energization of the control electrode is only indirectly connected therewith so that the potential 25 of the control electrode may easily differ by considerable amounts from the potential imparted thereto by the source. The above disadvantages are particularly objectionable in direct current inverting systems in which the sequence of energization of the control electrodes must be very accurate to secure proper operation of the system. Such disadvantages may be obviated by maintaining the control electrodes at such potential 30 that no flow of current may occur from the anodes of the device when such anodes are energized at their normal operating voltages. Such flow of current may then be initiated by momentarily increasing the potential of each anode to such a value that the associated control electrode becomes inactive.

It is therefore among the objects of the present invention to provide a control system for electron discharge devices of the gaseous or of the vapor type in which the flow of current 40 through an anode cannot occur upon energization of such anode at the normal operating voltage thereof.

Another object of the present invention is to provide a control system for electron discharge devices of gaseous or of the vapor type in which

the flow of current through an anode may be initiated by means other than the control electrodes associated therewith.

Another object of the present invention is to provide a control system for electron discharge devices of gaseous or of the vapor type in which the flow of current through an anode may be initiated by momentary energization of such anode at a voltage higher than the normal operating voltage thereof.

Another object of the present invention is to provide a control system for electron discharge devices of gaseous or of the vapor type in which the anodes of the device may sequentially receive control voltages through auxiliary electron discharge devices.

Objects and advantages other than those above set forth will be apparent from the following description when read in connection with the accompanying drawing which diagrammatically illustrates one embodiment of the present invention in which the anodes of a six phase electron discharge device operable as an electric current rectifier may be sequentially energized at control potentials through a plurality of auxiliary electron discharge devices.

Referring more particularly to the drawing by characters of reference, reference numeral 6 designates an alternating current supply line herein illustrated as a three phase line for the reason 30 that such type of line is most frequently utilized in practice. Line 6 energizes the delta connected primary winding 7 of a transformer having a secondary winding 8 comprising a plurality of portions such as 8a inter-connected in star to form 35 a neutral point. Transformer 7, 8 may also be provided with a six phase tertiary winding 9 the purpose of which will appear hereinafter. The different portions of winding 8 are severally connected through a plurality of reactors such as 11 40 with anodes such as 12 of an electron discharge device 13 having a cathode 14. Electron discharge device 13 is herein shown as being of the metallic vapor arcing type and is assumed to be provided with the usual ignition and excitation means (not 45 shown). Device 13 is assumed in the present disclosure to be operable as an electric current rectifier and cathode 14 thereof is therefore connected with the positive conductor 16 of a direct current output circuit having the negative conductor 50 17 thereof connected with the neutral point of winding 8. Rectifier 13 is provided with a plurality of control electrodes such as 18 which are severally energized through resistance such as 21 55 from a battery 19 connected with cathode 14 of 55.

the rectifier. The construction of the control electrodes is assumed to be such that, when such control electrodes are energized from battery 19, current may not flow through the anodes of the rectifier when such anodes are energized at their operating voltages but may flow when such anodes momentarily receive a voltage which is considerably higher than the normal operating peak voltage thereof.

- 10 Each anode such as 12 is connected with the cathode 22 of an electron discharge device 23 having a control electrode 24 and an anode 26. Device 23 is herein illustrated as being of the hot cathode type having a cathodic filament heated by means of current drawn from a suitable source such as one of the portions of winding 9. Anode 26 is connected with cathode 14 of the rectifier through the secondary winding 27 of a transformer having a primary winding 28 energized from line 6 through an adjustable condenser 29 and an adjustable reactor 31. Control electrode 24 of the device is connected with cathode 22 thereof through the secondary winding 32 of another transformer having a primary winding 33 energized from line 6 through an adjustable condenser 34 and an adjustable reactor 36. It will be understood that members 11 and 21 to 36 inclusive will be required in numbers equal to the number of anodes of rectifier 13, such number being six in the present embodiment, but that only one of each of such members are illustrated in the drawing for the purpose of simplifying the drawing. The plurality of transformers 27, 28 and 32, 33 as a whole must receive six phase currents from line 6 and, as such line is a three phase line, six phase currents may be obtained therefrom by utilizing each pair of conductors twice, but applying the identical voltages thus obtained in reverse connections.
- 40 In operation, assuming the system to be connected as shown in the drawing and line 6 being energized, winding 7 is energized from line 6 with the result that winding 8 impresses six phase potentials on the several anodes of rectifier 13. Winding 9 energizes the filaments 22 of devices 23 which are therefore operable as electric current rectifiers. As already stated above, it is assumed that, when the control electrodes of rectifier 13 are energized from battery 19 and the anodes of the rectifiers are energized at their normal operating voltages from winding 8, no current may flow through the rectifier. Assuming that, at the instant considered, anode 12 is at a positive potential with respect to cathode 14 and that at such instant it is desired to initiate the flow of current through such anode, reactor 31 and condenser 29 are so adjusted that winding 27 impresses, between anode 26 of device 23 and cathode 14 of the rectifier, a voltage considerably in excess of the positive voltage of winding portion 8a. Reactor 36 and condenser 34 are then so adjusted that, at the instant considered, control electrode 24 is brought to such potential as to permit flow of current between anode 26 and cathode 22 of device 23. The voltage of winding 27 is thus impressed between anode 12 and cathode 14 of rectifier 13 in an open circuit over anode 26 and cathode 22 of device 23. Such voltage is also impressed on a closed circuit comprising reactor 11, winding portion 8a, conductor 17, the load connected therewith (not shown) and conductor 16 but, due to the presence of reactor 11, such voltage remains impressed at substantially the full value thereof between anode 12 and cathode 14 for a sufficient period of time to permit initia-

tion of the flow of current from anode 12 to cathode 14. Current then flows from winding portion 8a over reactor 11, anode 12, cathode 14, conductors 16 and 17 to the neutral point of winding 8 as is well known in the art; such flow of current continuing as long as anode 12 is positive with respect to cathode 14 and is no longer influenced by the presence of control electrode 18 or by the potential of winding 27. During such flow of current, winding 27 is short circuited over device 23 and rectifier 13 thus causing the entire voltage of line 6 to appear across condenser 29 and reactor 31 which cooperate to limit the current flowing through winding 28. Such cycle of energization is repeated sequentially for each anode 15 of rectifier 13 during each cycle of the voltage of line 6 to permit the flow of a substantially uniform current to the output circuit of rectifier 13.

The moment of the voltage cycle of line 6 at which flow of current is initiated in anode 12 may be varied by varying the adjustment of condenser 34 or of reactor 36. Thereby also regulating the average voltage of the output circuit and the amount of current flowing therethrough.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In a control system for an electron discharge device, an alternating current line, an electron discharge device of the vapor type having a plurality of anodes, a transformer connecting said line with the anodes of said device, static means severally associated with the anodes to prevent operation thereof, and an electron discharge device associated with each of the anodes of the first said device to cause operation thereof during portions of the potential cycle in said line, the last said device being connected with the anodes and with the cathode of the first said device and with said line.

2. In a control system for an electron discharge device, an alternating current line, an electron discharge device of the vapor type having a plurality of anodes and a cathode, a transformer connecting said line with the anodes of said device, static means severally associated with the anodes to prevent operation thereof, an electron discharge device associated with each of the anodes of the first said device to cause operation thereof during portions of the potential cycle in said line, the last said device being connected with the anodes and with the cathode of the first said device, and means connecting the last said devices with said line to cause phase displacement of the potential applied thereto relative to the potential applied to the first said device.

3. In a control system for an electron discharge device, an alternating current line, an electron discharge device of the vapor type having a plurality of anodes and a cathode, a transformer connecting said line with the anodes of said device, static means severally associated with the anodes to prevent operation thereof, an electron discharge device associated with each of the anodes of the first said device to cause operation thereof during portions of the potential cycle in said line, the last said devices being connected with the anodes and with the cathode of

- the first said device, condensers connected with each of the last said devices, and a reactor connecting each of said condensers with said line, said condensers and said reactors being variable to permit variation of the phase of the potential applied to the last said devices from said line relative to the phase of the potential applied to the first said device from said line.
4. In a control system for an electron discharge device, an alternating current line, an electron discharge device of the vapor type having a plurality of anodes and a cathode, a transformer connecting said line with the anodes of said device, static means severally associated with the anodes to prevent operation thereof, electron discharge devices each having an anode connected with the cathode of the first said device and a control electrode connected with said line, transformers connected with the anodes and the control electrodes of the last said devices, and means connecting said transformers with said line to cause phase displacement of the potential applied to said transformers relative to the potential applied to the first said device.
5. In a control system for an electron discharge device, an alternating current line, an electron discharge device of the vapor type having a plurality of anodes and a cathode, a transformer connecting said line with the anodes of said device, said transformer having a tertiary winding, means comprising a source of current connected with said cathode and with said control electrodes for applying thereto a potential negative relative to the potential of said cathode, an electron discharge device associated with each of the anodes of the first said device and having a cathode connected with the tertiary winding of said transformer to cause electron discharge therefrom, and variable means connecting the anodes and the control electrodes of the last said devices with said line to cause phase displacement of the potential applied thereto relative to the potential applied to the first said device.
6. In a control system for an electron discharge device, an alternating current line, an electron discharge device of the vapor type having a plurality of anodes and a cathode, a transformer connecting said line with the anodes of said device, static means severally associated with the anodes to prevent operation thereof during portions of the potential cycle in said line, said devices each having an anode and a control electrode, and means connecting the anodes of the control electrodes of the last said devices with said line to cause phase displacement of the potential applied to the last said device relative to the potential applied to the first said device.
7. In a control system for an electron discharge device, an alternating current line, an electron discharge device of the vapor type having a plurality of anodes and a cathode, a transformer connecting said line with the anodes of said device, static means severally associated with the anodes to prevent operation thereof, electron discharge devices each having an anode connected with the cathode of the first said device and a cathode connected with an anode of the first said device and a control electrode connected with said line, and means severally connecting the anodes and the control electrodes of the last said devices with said line to cause operation of the anodes of the first said device only during portions of the potential cycle in said line.
8. In a control system for an electron discharge device, an alternating current line, an electron discharge device of the vapor type having a plurality of anodes and a cathode, a transformer connecting said line with the anodes of said device, said transformer having a tertiary winding, means comprising a source of current connected with said cathode and with said control electrodes for applying thereto a potential negative relative to the potential of said cathode, an electron discharge device associated with each of the anodes of the first said device and having a cathode connected with the tertiary winding of said transformer to cause electron discharge therefrom, and variable means connecting the anodes and the control electrodes of the last said devices with said line to cause phase displacement of the potential applied thereto relative to the potential applied to the first said device.
9. In a control system for an electron discharge device, an alternating current line, an electron discharge device having anodes with associated control electrodes and a cathode, the anodes being connected with said line, a source of potential negative relative to the potential of the cathode of said device, the control electrodes of said device being continuously connected with said source to prevent operation of the anodes thereof at the operating potentials applied thereto from said line, and means for sequentially impressing potential surges on the anodes of said device higher than the operating potentials thereof to cause flow of current therethrough.
10. In a control system, in combination with an electric current supply circuit, an electric current load circuit, and an electron discharge device comprising a cathode and an anode interconnecting said circuits and forming electrodes for the flow of current supplied by said supply circuit to said load circuit by way of arcs when established therebetween, of means for preventing the establishment of said arcs at the potentials of either of said circuits, and means connected with said anode and impressing thereon potential of such sign and magnitude and during such moments as to initiate said arcs, the potential of said supply circuit being of such magnitude as to maintain said arcs.

ARTHUR GAUDENZI.
